DESIGN FOR A COMBINED PICTURE FRAME AND WHATNOT OR SIMILAR ARTICLE

Herbert S. Johnson, Chicago, Ill.

Application March 31, 1944, Serial No. 113,100

Term of patent 7 years

(CL D29—20)

To all whom it may concern:

Be it known that I, Herbert S. Johnson, a citizen of the United States and resident of Chicago, in the county of Cook and State of Illinois, have invented a new, original, and ornamental Design for a Combined Picture Frame and Whatnot or Similar Article, of which the following is a specification, reference being had to the accompanying drawing, forming a part thereof.

In the drawing,

Figure 1 is a perspective view of a combined picture frame and whatnot, or similar article, showing my new design;

I claim:

The ornamental design for a combined picture frame and whatnot or similar article, as shown.

HERBERT S. JOHNSON.
